UNITED STATES PATENT OFFICE.

WILLIAM D. JONES, OF POUGHKEEPSIE, NEW YORK, ASSIGNOR TO HENRY WHINFIELD.

IMPROVEMENT IN PROPELLERS.

Specification forming part of Letters Patent No. 12,752, dated April 17, 1855.

To all whom it may concern:

Be it known that I, WILLIAM D. JONES, of the city of Poughkeepsie, in the county of Dutchess and State of New York, have invented a new and useful Machine for Propelling Steam or other Vessels; and I do hereby declare that the following is a full, clear, and exact description of the construction and operation of the same, reference being had to the annexed drawings, making a part of this specification, in which—

Figure 1 is an elevation or a stern view when attached to a vessel. Fig. 2 is a sectional view, and Fig. 3 is a perspective side view.

A are the disks or wheels or their equivalents; B B, the shafts or axles; C C, the paddles or buckets; D, the connecting ball-and-socket joint; E, the driving-cogs on disks or wheels; F F, the two driving-pinions; G G, the hinges or their equivalents; H H, the connecting-rings or their equivalents, I denoting the point when the disks or wheels are nearest together and no resistance from the paddles or buckets, and K denoting the point when the disks or wheels are farthest apart and have the greatest power of propulsion.

To enable others skilled in the art to make and use my invention, I will proceed to describe its construction and operation.

I construct my conical propeller by placing two circular wheels A A or disks or their equivalents, with or without arms, so constructed and set that their axes or shafts B B stand at about one hundred and twenty degrees from each other, more or less, and that the peripheries of said disks or wheels or their equivalents touch each other, or nearly so, at one point, while the faces of said disks or wheels A A diverge from each other at about sixty degrees, more or less, in consequence of the inclination of their axes, and between and to these said disks or wheels or their equivalents propellers or buckets C C or their equivalents are attached radially, and of a length sufficient to extend to half the distance between the said disks or wheels or their equivalents, and there and then connected and acting as hereinafter detailed. These propelling disks or wheels A A are driven in the same direction and at a uniform speed by ball-and-socket or universal joints connecting on the interior ends of said shafts

at D, or by means of cogs on the edges or on the sides or faces of said disks or wheels at E, matching into each other at the point where the disks or wheels meet, or else by two pinions F F between the said disks or wheels gearing into teeth on the faces of said disks or wheels near their edges, or any other suitable means. Onto the faces of these wheels or disks one or more buckets or paddles C C or their equivalents are attached, standing radially on the face of each of the disks or wheels or their equivalents, and the shape of each of these buckets or paddles C C is such as to occupy and extend to one-half the distance between the said disks or wheels when farthest apart, and, meeting each other, are connected or joined at G in the center, and occupying the whole space between the said disks or wheels or their equivalents, and pairs of these buckets or paddles C C, thus formed, connected, and attached to these disks or wheels by radial hinges or joints D D, extending across between the said disks or wheels, are connected at their outer or moving ends by means of a ring G or suitable joint or its equivalent. The operation of these buckets or paddles as they revolve with and between these inclined wheels or disks is that when any of the buckets or paddles C C have reached the point I, where the disks or wheels are nearest together, the said buckets or paddles are closed or folded down flat, or nearly so, onto the face of said disks or wheels and pass through the water without offering any resistance; but as said buckets or paddles are moved on by the rotation of the disks or wheels the buckets or paddles C C will evolve and extend, as at K, from the face of the wheels or disks until said pair of buckets or paddles stand at right angles to the faces of the wheels or disks at the point K, where said disks or wheels are the farthest apart from each other, thereby producing continual and direct propulsion against the water at one point and no resistance at the other point, and the continued rotation of the disks or wheels turns up or closes said buckets or paddles and causes them to extend and evolve, as the case may be, so that the hinges in their revolution with the disks or wheels approach to or recede from each other until they lie flat against, or nearly so, or at right angles with the faces or planes of the said disks or wheels or their

equivalents before detailed. One or more pairs of paddles or buckets or their equivalents may be used between the said disks or wheels or their equivalents, and one or more of the propellers thus formed may be applied to the stern or sides or bottom of the ship or vessel in any convenient or suitable manner.

What I claim as my invention, and desire to secure by Letters Patent, is—

The arrangement and combination of the parts forming a propeller, as fully set forth in the foregoing specification, for the purposes above mentioned.

WILLIAM D. JONES.
